UNITED STATES PATENT OFFICE.

FREDERICK MAX PORITZ, OF NEW YORK, N. Y., ASSIGNOR TO STAR CHANDELIER COMPANY, OF NEW YORK, N. Y., A CORPORATION OF NEW YORK.

DESIGN FOR A CHANDELIER.

58,104.

Specification for Design.

Patented June 7, 1921.

Application filed May 12, 1920. Serial No. 380,930. Term of patent 3½ years.

To all whom it may concern:

Be it known that I, FREDERICK MAX PORITZ, a citizen of Germany, residing at the city of New York, borough of Manhattan, county of New York, and State of New York, have invented a new, original, and ornamental Design for a Chandelier, of which the following is a specification, reference being had to the accompanying drawing, forming a part thereof.

The figure shown in the drawing is a perspective view of a chandelier embodying my new design.

The essence of my invention resides in the design of the chandelier as a whole, substantially as shown and described. It is to be understood that my claim includes all substantial equivalents of my design as shown and described.

I claim:

The ornamental design for a chandelier substantially as shown and described.

FREDERICK MAX PORITZ.
